UNITED STATES PATENT OFFICE

2,533,157

COMBINED FILLING AND VIBRATING DEVICE HAVING AN ELONGATED VIBRATORY BAG MEMBER

Ralph E. Williams, Chicago, Ill., assignor to
B.F. Gump Co., a corporation of Illinois

Application February 15, 1945, Serial No. 577,948

1 Claim. (Cl. 226—55)

1

My invention relates to a bag filling machine. One purpose is to provide a bag filling machine in which the bag is suspended by the neck or top during filling.

Another purpose is to provide a bag filling machine in which the bag, while suspended from its upper end, is vibrated laterally to pack and form the material in the bag.

Another purpose is to provide a bag filling machine which fills the bag while the bag is in position above a conveyor, whereby the bag when filled, can be released directly to the conveyor without the necessity of intermediate handling.

Another purpose is to provide a bag filler which tends to form or flatten a filled bag and the charge within it.

Another purpose is to provide a labor saving bag filling assembly which avoids the necessity of manually lifting or moving the filled bags.

Other objects will appear from time to time throughout the specification and claim.

My invention is illustrated more or less diagrammatically in the accompanying drawings, wherein:

Figure 1 is a plan view;

Figure 2 is a side elevation;

Figure 3 is a plan view of a variant form; and

Figure 4 is a side elevation of the structure shown in Figure 3.

Like parts are indicated by like characters throughout the specification and drawings.

1 generally indicates any suitable base upon which may be mounted a motor 2 with its pulley 3. 4 generally indicates an A-frame, of which there may be two, mounted on the base 1. Pivoted to the A-frames, as at 5, is a vibrator generally indicated as 6 which has a free bottom edge 7. The vibrator is shown as somewhat inclined from the vertical. The vibrator may be vibrated for example by the link or connection 8 having lugs 9 carrying pins 10 which interpenetrate with lugs 11 extending from the vibrator 7. The vibrator may, if desired, be flat or generally plane, as shown in Figures 1 and 2, or it may be more or less formed to the contour of the bag. It is important that the vibrator be so formed and positioned that the bag X, when released, will drop downwardly by gravity upon any suitable conveyor 12. The details of the conveyor do not of themselves form part of the present invention but I may employ, for example, an endless conveyor or belt driven by any suitable actuating means not herein shown, or any other suitable conveyor.

The connection or plate 8 has secured to it a bearing block 14, through which passes the eccentric portion 15 of the power driven shaft 16. The shaft may be journaled in any suitable bearing assemblies 17 on the base 1 and may be rotated by a combined pulley and fly wheel 19,

2

driven for example by V-belts 20 from the motor drive pulley 3. The fly wheel 19 may be suitably counterweighted. It will be understood that in response to the rotation of the shaft of the motor 2, the vibrating shaft 16 will be rapidly rotated. The rotation of the shaft 16 will rotate the eccentric and will thus impart a relatively high frequency vibration to the vibrating connection 8. This vibration in turn will cause a rapid vibration or oscillation of the bag contacting vibrator 6 about its center 5.

The bag X is preferably suspended by its upper edge or neck during the feeding operation. I illustrate any suitable feed spout 20 having a bottom holding enlargement 21 and an upper limit flange 22. In applying the bag X to the spout, it may be threaded on the spout 20 with its upper edge at or near the limit flange 22. Any suitable means such as the twisting device 59, may then be employed for holding or locking the bag X to the spout 20. Suitable twisting or tensioning means are shown in copending application Serial No. 576,260 filed in the United States Patent Office on February 5, 1945, now Patent No. 2,430,073. However, since the particular securing means does not form part of the present invention, it is not shown in detail herein. Any suitable means for securing the bag by its upper edge may be employed, whereby the bag X is suspended from the feed spout 20. It is advantageous that the bag be permitted to drop or slide by gravity upon the conveyor 12 after the filling and settling process is completed.

As shown in Figure 2, I find it advantageous so to position the spout 20 in relation to the vibrator 6 that the bag X will be held by gravity against the vibrator 6 during the filling process. It is also advantageous, in order to prevent tearing of the neck of bag, to have the axis of the bag generally parallel with the bag engaging face of the vibrating element 6. Stated otherwise, it is important to ensure an even distribution of the gravitational load of the bag charge on the neck of the bag. Therefore it may be disadvantageous to have the axis of the spout 20 perpendicular, as such a spout arrangement may result in an uneven load on the fabric of the bag when the bag has received the charge and is in the inclined position in which it is shown in Figure 2.

With reference to the forms of Figures 3 and 4, I illustrate a vibrator which may advantageously be used with a vertical axised spout and an underlying conveyor. The base carries A-frames 4a. The apex of each A-frame is located somewhat to the right of the side of its base, as shown in Figure 4. The motor 2a with its pulley 3a rotates the vibrating shaft 16a with its eccentric portion 15a. This eccentric, through the vibrating connection 8a, vibrates a bag surrounding channel member having opposite gen-

erally vertical side elements 30 and 31 connected by a connecting wall portion 32. The faces of the walls 30 and 31 are preferably generally vertical and parallel with the axis of the vertically suspended bag Y. The bag Y may be secured in the same manner as the bag X, except that the spout 20a with its holding flange 21a has a generally vertical axis. The conveyor 12a underlies the bag. It will be understood that the conveyor 12a is moved in the direction of the arrow of Figure 3 so that when a particular bag Y is released, it drops upon the conveyor 12a and is moved by the conveyor outwardly through the open side of the vibrating channel.

It will be realized that whereas I have shown and described an operative device, still many changes might be made in the size, shape, number and arrangement of parts without departing materially from the spirit of my invention. I wish, therefore, that my showing be taken as in a broad sense diagrammatic and illustrative, rather than as limiting me to my precise showing.

Where I employ the term "bag" in the claim, I wish this term to be interpreted as of sufficient breadth to cover any suitable container which is adapted to be packed by the mechanism and method herein described. It is practical under some circumstances to support boxes, barrels or other containers by an upper portion and vibrate and pack them in accordance with the disclosure herein made.

The use and operation of my invention are as follows:

In both forms of the device, the bag X or Y is suspended by its upper edge or neck during the filling operation. Any suitable charge of material is released through the spout 20 or 20a into the interior of the bag, the securing means for the bag being effective to support the bag from above and to avoid the necessity of any underlying supporting means for the bag. I have diagrammatically illustrated bag tensioning means 50 in Figures 2 and 4, such as are shown in detail in a co-pending application. The upper edge of the bag is drawn in or tensioned about the spout 20 or 20a which, with the flange 21 or 21a, prevents the escape of the bag until the securing means 50 is released. The bag, during the admission of the charge, and when charged, is subjected to lateral vibration.

In the form of Figure 2, the vibrating element 6 slightly underlies the bag X, causes gravity to maintain the bag in contact with the member 6 during its vibration. In the form of Figures 3 and 4, the bag is contained between the opposed vibrating walls 30 and 31, which slap back and forth against opposite sides of the bag and tend to flatten the bag and give it a desirable form. In both forms of the device the bag, when properly charged and packed, is released by releasing the securing means 50. The bag then drops upon the conveyor 12 or 12a and is conveyed thereby for further handling or disposal. The vibrating member 6 or the members 30 and 31 guide the bag in its gravitational movement downwardly to the conveyor and avoid the necessity of any manual lifting or lateral moving of the bag.

A major advantage of the invention above described is the provision of a bag packing assembly which delivers the filled or packed bag directly to a conveyor without the necessity of intermediate handling. For example, in either form of the device the result of releasing the securing means 50 is to permit the packed bag to

move by gravity downwardly upon and be supported upon the conveyor 12 or 12a. The conveyor, whether continuously or intermittently operated, is then effective to remove the bag from the packing area. This is highly advantageous because the packed bags may be heavy and the avoidance of the manual effort of lifting the bag from the packing zone to the conveyor is important. Thus a manual operation is eliminated, with a consequent saving of time and labor and with a speed up in production. The task of manually moving a large filled sack is hard on the laborer and its avoidance is much to be desired. The filled bag can be carried on the conveyor to or through any further stages of treatment without the necessity of manually lifting the bag.

I claim:

In a bag packer, a base, an elongated vibratory member having an upper end pivotally supported on said base, a drive for laterally vibrating said member including a power driven member on said base laterally offset with respect to said pivotal support and an actuating link connection between the power driven member and the vibratory member for swinging said vibratory member in an arc about the pivoted upper end thereof, a bag support positioned adjacent to and above the upper end of the vibratory member, and spaced therefrom, whereby the vibratory member is free to move independently of the bag support, the vibratory member being supported to extend downwardly and outwardly from its pivotal support at an angle toward a bag suspended from the bag support and being positioned to underlie the bag support and a bag suspended therefrom substantially throughout the arc of movement of the vibratory member, whereby gravity is substantially constantly effective to urge a bag suspended on the bag support toward the vibratory member, said vibratory member having a bag engaging portion extending generally from end to end of the bag, whereby the contents of the bag are simultaneously vibrated from end to end of the bag, the angle of the bag engaging portion of the vibratory member being substantially less than the angle of repose, whereby when the bag is released from the bag support it is free to slide gravitally downwardly along and from the vibratory member, the lower end of the vibratory member being formed to permit the bag to move freely therefrom when the bag is released from the bag support.

RALPH E. WILLIAMS.
